UNITED STATES PATENT OFFICE.

JOHN J. O'BRIEN, OF ST. LOUIS, MISSOURI, ASSIGNOR TO THE JOHN O'BRIEN BOILER WORKS COMPANY, OF SAME PLACE.

DESIGN FOR A BOILER-BRACE.

SPECIFICATION forming part of Design No. 34,551, dated May 21, 1901.

Application filed April 15, 1901. Serial No. 56,022. Term of patent 14 years.

To all whom it may concern:

Be it known that I, JOHN J. O'BRIEN, a citizen of the United States, residing in the city of St. Louis, State of Missouri, have invented 5 and produced a new and original Design for a Boiler-Brace, of which the following is a full, clear, and exact description, reference being had to the accompanying drawings, forming part of this specification.

Figure I is a top perspective view of my new design. Fig. II is a side perspective view of the same.

As shown in the drawings, my design con-

sists of a body 1, at one end of which is a head 2, having two perforated prongs 3 set at an angle to the body 1 and between which is a depressed portion 4. At the other end of the body is a perforated flat portion 5, set at an angle to the body 1.

I claim as my invention—

The design for a boiler-brace herein shown and described.

JOHN J. O'BRIEN.

In presence of—

E. S. KNIGHT,
N. V. ALEXANDER.
